United States Patent Office.

CHARLES MONTAGUE, OF BOSTON, MASSACHUSETTS, ASSIGNOR TO CYRIL C. CHILD, OF SAME PLACE.

Letters Patent No. 98,088, dated December 21, 1869.

IMPROVEMENT IN PRINTING-PRESSES.

The Schedule referred to in these Letters Patent and making part of the same.

To all whom it may concern:

Be it known that I, CHARLES MONTAGUE, of Boston, in the county of Suffolk, and State of Massachusetts, have invented certain new and useful Improvements in Printing-Presses; and I do hereby declare the following to be a full, clear, and exact description of the same, taken in connection with the accompanying drawings, making a part of this specification, and the letters of reference marked thereon, in which—

Figure 1 is a side elevation of my improved press.

Figure 2 is an end elevation, with back girt removed, and showing the longitudinal girt, which forms the inner bearing of the crank-shaft in section.

Figure 3 is a plan, with feed-table removed.

Figure 4 is a vertical section on line *y y* on fig. 2.

Figure 5 is a section on a crooked line, the upper portion being cut on line *x x*, and the lower portion on line *v v* on fig. 2.

My invention relates, in the first place, to the means employed to automatically raise the impression cylinder, while the bed is moving in one direction, and lower it again while the bed is moving in the other direction, and also to the means provided for arresting the impression at the will of the operator; and consists in hanging the impression cylinder in bearings on radius arms or levers, one end of each of which is pivoted to the frame, so that the lever shall be in nearly a horizontal position, the movable end of said levers being attached to bars or rods fitted to slide in bearings attached to the frames, and provided with a pin at the lower end of each, which fits into vibrating cams, which are operated by a dog, pivoted to the side of the bed, as will be more fully described.

It also consists in the use of a movable wedge, so arranged, in combination with the dog above named, that it will be inoperative during a great portion of the time, but so that it may be moved into a position in the path of said dog, so that as the bed moves from the front to the rear, the dog will be lifted thereby and made to pass over the vibrating cam without moving it, and thus allow the cylinder to be held in its raised position during the movement of the bed from front to rear, and thus prevent an impression being given, at the will of the operator.

My invention relates, in the second place, to the mechanism for operating the nippers; and consists in the use, in combination with a reciprocating bed, operated by an extensible vibrating lever, of an arm, attached to one end of the nipper-shaft by its middle, one side of which is provided with a lip, slightly curved at each end and placed in such a position that the revolution of the cylinder will cause it to strike a pin fixed in the frame at a point somewhat nearer the axis of the cylinder than the axis of the nipper-shaft, and open the nippers, preparatory to being closed upon a sheet, the operation of rotating the nipper-shaft and

holding the sheet on the cylinder being greatly facilitated by the use of a spring, which will be described hereafter.

It also consists in the use, in combination with said bed and cylinder, operated as above described, of a movable pin, placed somewhat further from the axis of the cylinder than the nipper-shaft, by means of which the nipper-shaft may be rotated in the opposite direction, and close the nippers on to the sheet, said pin being connected to a lever, which is acted upon by a cam surface or wedge on the edge of the bed in such a manner that the nippers will be closed but once to every two revolutions of the cylinder.

In the drawings—

A represents the side frames of the machine, connected together by the tie-girts *A'*.

B is the type-bed, fitted to move on slides *C*, and moved by the lever *D*, made in two parts, the lower portion being attached to the rocker shaft *D¹*, and the upper portion *D²* being fitted to suitable bearings in the lower portion, so that it may move out of or into the lower portion *D*, and so that, as its upper end being attached to the under side of the bed, moves in a straight line when said lever is moved by the action of the crank *E*, and its pin *a* and the block *b* working in the slot *e*, the length of the whole lever will constantly vary, according to the position of the bed.

F is the main crank-shaft; and *G* is a gear-wheel, made fast to the outer end of said shaft, and is driven by the pinion *H*, and hand-crank *I*, or a pulley may be substituted for the crank *I*, and the machine be driven by steam or water-power.

J is a gear-wheel, fitted to revolve on a stud set in the stand *K*; in such a manner that the axis of the gear-wheel *J* shall be eccentric to the axis of the crank-shaft *F*.

The gear-wheel *J* is provided with a crank-pin, *d*, projecting inwardly, and fitting into the slot *e*, cut in the gear-wheel *G*, and shown in dotted lines in fig. 1.

The length of the slot *e* must be equal to double the distance between the centres of the gear-wheel *J* and the centre of the shaft *G*, added to the diameter of the pin *d*, and be of the necessary form to give the required variableness to the rotation of the gear-wheel *J*, to give the requisite motion to the cylinder *L*, to insure its moving in exact unison with the type-bed during the whole time of taking an impression.

M, *N*, and *O*, are gear-wheels, through which the motion of the gear-wheel *J* is transmitted to the cylinder *L*, and are so arranged that the cylinder *L* may be raised or lowered without effecting the operation of the gears.

a' a are radius arms, pivoted to the frame in a horizontal position, in the movable end of which are formed the bearings for the cylinder *L*.

b' b are bars or rods, fitted to slide in bearings on

the frame, and attached by their upper ends to the movable ends of the radius arms a' and carrying-pins $c' c'$, at their lower ends, which fit into the cam-slots $d' d'$, formed in the vibrating levers e^1 and e^2 , attached to the frame by fulerum-pins f .

$g' g'$ are two links, and h' , a lever, which serve to connect the two braces e^1 and e^2 together, so that any motion of one of said levers will be transmitted to the other.

i is a cam, on the main crank-shaft, which, acting upon the lower end of the lever e^2 , raises the cylinder.

j is a dog, pivoted to the edge of the bed in such a position that when the bed moves from front to rear, it will strike the upper end of the lever e^1 , and moving it till the pin c' is in the lowest portion of the slot d' , when the cylinder will be in the proper position to give impression to the sheet.

k is a spring, wedge, or cam, which is used to throw the dog j out of gear, or prevent its action when it is desired to prevent a sheet from being printed, and l is a handle, by which it is operated.

P is a rocker-shaft, to which the nippers $g' g$ are attached, and h is an arm, made fast to one end of said shaft, by which it is rotated, and i is a spring, attached by one end to the end of the cylinder, while the other end is made fast to the arm h , and serves the purpose of holding the nippers with considerable tension upon them, whether they are closed or open.

j is a pin, fixed in the frame, which serves the purpose of opening the nippers by the striking of the arm h against it during the revolution of the cylinder, said cylinder rotating in the direction indicated by the arrow.

h is a pin, so placed that the striking of the arm h against it will cause the rocker-shaft P to be revolved in the opposite direction, and close the nippers on to the sheet.

The pin k is fitted to slide in a bearing in the frame, and is attached to the upper end of the lever l , hung by its centre to a stand on the outside of the frame, the lower end of said lever having another slide-rod, m , attached thereto, and extending through the frame in such a position that it may be acted upon by the cam or wedge surface n , on the edge of the bed, and move the pin k into such a position that it will be struck by the arm h , and close the nippers.

o is a spring, which serves to throw the pin k back out of the path of the arm h , when the cam surface n has moved away from the pin m , and holds it there till the bed returns again and the cam surface n comes in contact with the pin m .

The operation of my improved press is as follows:

The sheets being placed upon the feed-table, and fed down to the nippers in the usual manner, and the machine being set in motion by revolving the crank I , the bed carrying the type-form will be moved from the rear of the machine to the front, and passing under the inking-rollers (not shown in the drawings) while the crank F is moving through about one-third of its revolution, and that being the lower portion, and at

about the time that the bed has arrived at the end of its movement in that direction, and while the cam surface n is holding the pin m , pushed out, and thereby holding the pin k in the proper position, the cylinder, by its revolution, will cause the arm h to strike the pin k , and cause the rocker-shaft P to be partially revolved, and close the nippers on to the sheet and carry it around with the cylinder at the same time the bed commences its return movement, and the dog coming in contact with the upper end of the lever e^1 , moves it, and by the action of the cam-slots $d' d'$ lowers the cylinder on to the form. Just at this point, the motion of the bed and the impression cylinder is made to correspond, and continues so to do until the impression is completed, this correspondence being effected by means of the two gears G and J , set eccentrically and connected by the pin d and slot e .

The motion of the machine being continued, the sheet will be carried around by the cylinder, until the forward edge of the sheet has arrived at the proper point to be discharged, when the arm h , on the niper-shaft P , comes in contact with the pin j , and opens the nippers, and the sheet is taken off by means of tapes, not shown in the drawings, in the usual manner.

Before the bed returns to the front, the cam i comes in contact with the lower end of the lever e^2 , and by the action of the slots $d' d'$ upon the pins $c' c'$, raises the cylinder so that the bed and "form" may pass under the cylinder without receiving any impression, and as the bed moves back, the dog passes over the lever e^1 without having any effect upon it.

If the operator wishes to prevent the next sheet from being printed, he will press upon the handle l , which will spring the wedge k into the path of the dog j , and said dog will be raised up so that it will pass over the lever e^1 without moving it, so that the bed will pass under the cylinder while it is in a raised position.

Having thus fully described the construction and operation of my improved press,

What I claim as new, and desire to secure by Letters Patent, is—

1. The combination of the cam-levers e^1 and e^2 , dog j , bed B , and cylinder L , constructed and operating substantially as described, for the purpose specified.
2. The spring wedge, k , for arresting the action of the dog j , constructed and operating substantially as described, for the purpose specified.
3. In combination, with a reciprocating type-bed, the cam-wedge n , pins m and k , lever l , spring o , and arm or dog h , constructed and operating substantially as described, for the purposes specified.

Executed at Boston, this 11th day of June, A. D. 1869.

CHAS. MONTAGUE.
